REFRIGERATION CONTROL SYSTEM

Alwin B. Newton, Minneapolis, Minn., assignor
to Minneapolis-Honeywell Regulator Com-
pany, Minneapolis, Minn., a corporation of
Delaware

Application November 28, 1938, Serial No. 242,723

15 Claims. (Cl. 62—4)

This invention relates to a multiple fixture mechanical refrigeration system and more particularly to a system wherein frequent defrosting of the evaporators in the various fixtures is assured.

Many methods have been proposed to control a system of this type, one of these being shown in the application of William L. McGrath, Serial No. 196,446, filed March 17, 1938. In one form of the invention illustrated in this application, a solenoid valve controls the flow of refrigerant to each evaporator, and a thermostat is located in each fixture to control the associated solenoid valve in accordance with the temperature in the fixture. The thermostats are connected in parallel to the compressor starting circuit and the compressor is maintained in operation as long as any of the thermostats are calling for cooling. As soon as all the thermostats become satisfied, the compressor shuts down and cannot become restarted until the suction pressure rises to a predetermined value, which value will not be attained until all of the evaporators have become defrosted. Accordingly, once the compressor has stopped, it cannot be restarted until all evaporators become defrosted, but in view of the fact that all of the fixture thermostats must be simultaneously satisfied in order to shut down the compressor, there is no assurance that frequent defrosting of the evaporators will occur. The reason for this is that due to varying load conditions in the various fixtures, a long time may elapse before each of the thermostats is satisfied at the same time since the thermostats will not necessarily cycle together. Accordingly, with this type of system, there is no definite assurance that frequent defrosting of the evaporators will take place.

The system illustrated in the second form of the invention of the McGrath application is designed to overcome this disadvantage of the above described system. In this arrangement, the thermostats in the various fixtures are arranged as described above, and a timer is provided to interrupt operation of the compressor at predetermined intervals. Whenever the compressor is shut down by the timer, it cannot be restarted until the suction pressure has risen above the defrosting value, but whenever the compressor is shut down by reason of all the thermostats being simultaneously satisfied, it can be restarted as soon as one of the thermostats again calls for cooling, regardless of the value of the suction pressure, unless the timer has operated in the meantime. Thus, this sys-

tem requires the provision of a timer mechanism, and in addition thereto, it has the disadvantage that a defrosting cycle will not commence if all the thermostats should be simultaneously satisfied, unless an operation of the timer mechanism takes place during this time.

In my copending application Serial No. 196,450, filed March 17, 1938, a system is illustrated which is designed to reduce the likelihood of the thermostats in the fixtures cycling in such a manner that they will not all be satisfied simultaneously in a system of the type shown in the first form of the invention of the McGrath application described above. In this application, heating elements are located in heating relationship with the thermostats, these heating elements being imbedded in heat absorbing masses which support the thermostats. During a defrosting period, when all of the thermostats have become satisfied, the heating elements are energized which causes the temperature of all of the thermostats to rise to a value in which they are all calling for cooling. Accordingly, when the suction pressure rises to the desired value at which all the evaporators are defrosted, all of the thermostats will be calling for cooling and the tendency will be for the thermostats to cycle together, and the chance of one or another thermostat always calling for cooling will be greatly reduced. This type of system is not entirely satisfactory however, since in certain cases, the thermostats may still so get out of step that a long time may elapse before a defrosting period starts, so that while this system reduces the danger of infrequent defrosting periods of the first system of the McGrath application, it does not entirely eliminate this danger.

In the application of George H. Fisher, Serial No. 232,606, filed September 30, 1938, a system somewhat similar to that shown in the McGrath application Serial No. 196,446 is illustrated for causing frequent defrosting of a multiple fixture refrigeration system. In this system, a defrosting period will take place whenever the thermostats in all of the fixtures become satisfied at the same time as in Figure 1 of the McGrath application, and in addition thereto, a timer is provided to shut down the compressor at definite intervals, thus insuring a defrosting period at definite intervals even if the various thermostats shouldn't become satisfied at the same time often enough to insure frequent defrosting. The compressor will also shut down if the suction pressure drops to a sufficiently low value. This system requires the provision of a timing mechanism, and

it may very likely happen that the timing mechanism may initiate a defrosting period soon after one has taken place by reason of all the thermostats becoming simultaneously satisfied, or by reason of the suction pressure dropping to a low enough value, and it is obviously undesirable that defrosting take place when unnecessary.

In accordance with the teaching of my invention, frequent defrosting of the evaporators is assured regardless of the relative temperature in the various fixtures and without the use of heaters with the thermostats or the use of a timing means. This is accomplished by having the thermostat in only one of the fixtures in control of the compressor, so that whenever the temperature in that fixture becomes satisfied, or the suction pressure in the system drops low enough, the compressor stops and cannot restart until the suction pressure rises to a high enough value to indicate that the evaporators are all defrosted. The temperatures of the other fixtures may be controlled by controlling the flow of refrigerant through the evaporators therein. This may be accomplished by providing a thermostatic expansion valve having an adjustable superheat setting, and adjusting the setting thereof in accordance with the temperature in the fixture to vary the degree of superheat in the evaporator and consequently the effective cooling area thereof. If it is desired to control the fixture to maintain a desired humidity rather than a desired temperature within the fixture, this may be conveniently done by varying the superheat setting. Another way in which the fixture temperature may be readily controlled is by providing an adjustable valve in the supply line to the expansion valve, and adjusting this valve in accordance with the temperature in the fixture to control the flow of refrigerant to the expansion valve.

It is therefore an object of my invention to provide, in a multiple fixture type mechanical refrigerating system a novel control arrangement whereby the conditions in each of the fixtures may be independently controlled and whereby frequent defrosting of all of the evaporators is assured.

Other objects and advantages will become apparent upon reference to the specification, claims, and appended drawing wherein is illustrated a preferred form of my invention.

Referring more particularly to the drawing, a refrigeration system is illustrated, this system comprising a compressor 10, a condenser 11, receiver 12, and evaporators 13, 14, and 15 which are connected in parallel in the system. The evaporators 13, 14, and 15 are located in fixtures 16, 17, and 18, respectively. Expansion valves 19, 20, and 21 control the flow of refrigerant into the evaporators 13, 14, and 15, respectively, the valves 19 and 21 being illustrated as any conventional form of thermostat expansion valve and the valve 20 as will be pointed out hereinafter being of a type wherein the superheat setting of the valve may be automatically adjusted in accordance with a condition in the fixture 17. When the compressor 10 is in operation, refrigerant flows through the pipe 22 into condenser 11 from which it flows into the receiver 12 and through the pipe 25 to the various expansion valves and returns by way of the pipe 26 to the inlet of the compressor 10, in a manner well known in the art.

The compressor 10 is driven by a motor 30 and this motor may be controlled by a control device of the type shown and described in application

Serial No. 196,447, filed by Albert L. Judson and Carl G. Kronmiller on March 17, 1938. For purposes of illustration, in this application this control device is generally represented by the reference character 31 and is shown to comprise a base 32 upon which is mounted a bellows 35. The bellows 35 is connected by a pipe 36 to the low pressure or suction line 26 of the refrigerating apparatus. The bellows 35 operates a lever 37 pivoted on a fulcrum member 38 against the action of a tension spring 39. One end of the tension spring 39 is connected to the lever 37 and the other end is connected to a nut 40 screw-threadedly mounted on a screw 41. By rotating the screw 41 the tension in the spring 39 is adjusted to calibrate the pressure setting of the bellows 35. The lever 37 carries an insulating pad 42 upon which is mounted a bridge member 43. The bridge member 43 carries a contact 44 which is adapted to engage a resilient contact member 45 carried by a terminal 46. The bridge member 43 also carries a contact 47 adapted to engage a resilient contact member 48 carried by a terminal 49. The contact members 45 and 48 are adjustably positioned by means of concentrically located and independently rotated cams 50 and 51. By rotating the cam 50 the position of the contact member 45 with respect to the contact member 44 may be varied and likewise by rotating the cam 51 the position of the contact member 48 may be varied with respect to the contact 47. For purposes of illustration it is assumed that the cams 50 and 51 are so positioned that upon an increase in suction pressure the contact 44 engages the contact member 45 at substantially 20 pounds and that the contact 47 engages the contact member 48 at substantially 35 pounds. Upon a decrease in pressure the contact 47 disengages the contact member 48 at 35 pounds and then the contact 44 disengages the contact member 45 at 20 pounds. It is assumed that when the pressure in the low pressure or suction line 26 rises to some value, say 32 pounds, that defrosting of the evaporators 13, 14 and 15 has occurred. Accordingly, the contact 47 is not moved into engagement with the contact member 48 until defrosting of all of the evaporators has occurred. Since the low pressure or suction pressure is a direct indication of evaporator temperature, then it may be said that the contacts 44 and 47 are operated in accordance with changes in evaporator temperature. If desired, the bellows 35 could be connected by a capillary tube to a bulb located adjacent one of the evaporators, the bulb containing a volatile fluid so that the bellows 35 would be operated in direct accordance with evaporator temperature, or could be connected to a plurality of bulbs, there being a bulb located adjacent each of the evaporators.

The unitary control arrangement 31 also includes a bellows 53 connected by a pipe 54 to the high pressure line 22 of the refrigerating apparatus. The bellows 53 operates a lever 55 fulcrumed on a fulcrum member 56 against the action of a tension spring 57. One end of the tension spring is connected to the lever 55 and the other end is connected to a nut 58 screw-threadedly mounted on a screw 59. By rotating the screw 59 the tension in the spring 57 may be adjusted to adjust the pressure setting of the bellows 53. The lever 55 carries an adjustable abutment member 60 having abutments 61 and 62. The abutment 61 is adapted to engage a resilient contact member 63 carried by a terminal 64.

Contact member 63 engages a contact 65. The abutment 62 is adapted to engage a resilient contact member 66 carried by the terminal 49. The contact member 66 engages a contact 67. For purposes of illustration, it is assumed that upon an increase in pressure the abutment 62 first engages the contact member 66 to move the contact member 66 out of engagement with the contact 67 when the high pressure rises to 135 pounds and the abutment 61 engages the contact member 63 to move the contact member 63 out of engagement with the contact 65 when the high pressure rises to 185 pounds. Upon a decrease in pressure contact member 63 engages contact 65 at 185 pounds and the contact member 66 engages the contact 67 at 135 pounds.

The unitary control arrangement 31 also includes a relay or starter generally designated at 68. This relay or starter comprises an operating coil 69 for operating a bridge member 70 with respect to maintaining contacts 71 and 72 and a bridge member 73 with respect to load contacts 74 and 75. When the operating coil 69 is energized the bridge member 70 is moved into engagement with the contacts 71 and 72 and the bridge member 73 is moved into engagement with the contacts 74 and 75. When the operating coil 69 is deenergized the bridge members 70 and 73 are moved out of engagement with their respective contacts by means of springs, gravity, or other means, not shown.

The unitary control arrangement 31 may also include an overload cut-out generally designated at 71. This overload cut-out may include a heater element 78 connected between a terminal 79 and the load contact 74 for heating a thermostatic element which trips open contacts 80 and 81 upon the occurrence of an overload condition. The contacts 80 and 81 may be manually reclosed by means of a reset arm 82.

Power is supplied to the unitary control arrangement 31 by means of line wires 88 and 89 leading from some source of power (not shown). The line wire 88 is connected to the contact 65 and the line wire 89 is connected to the power terminal 86. The compressor motor 30 is connected by wires 90 and 91 across the relay load contact 75 and the power terminal 86. Terminal 46 is connected by means of a wire 100 to an electrode 101 in a mercury switch 102 which is located in the fixture 16. This switch 102 is carried by an arm 103 pivoted at 104 and biased by means of a spring 105 into engagement with the upper portion of a bellows 106 provided with a suitable volatile fill whereupon this bellows expands or contracts in accordance with variations in temperature in the fixture 16. The other terminal 107 of the switch 102 is connected by means of a wire 108 to the terminal 64. The contact 67 is connected by means of a conductor 110 to the relay maintaining contact 72 which in turn is connected by means of a conductor 111 to the contact 80 of the overload cut-out 71. The contact 81 is connected by a conductor 112 to the operating coil 69 which is in turn connected by a conductor 113 to the power terminal 86. The bridge member 43 is connected by a conductor 115 to the relay contact 71. The contact 65 is connected by a conductor 116 to the terminal 79 of the overload cut-out 71.

Assuming the parts in the position shown, the high pressure is less than 135 pounds, the low pressure is less than 35 pounds, and the temperature of the fixture 16 is less than 40°, hence the relay or starter 68 is dropped out and the com-

pressor is not operating. Assume now that the low pressure rises to 35 pounds by reason of the defrosting of all of the evaporators and that the temperature within the fixture 16 rises to 40°. When this occurs, a starting circuit is completed from the line wire 88 through contact 65, contact member 63, terminal 64, wire 108, electrodes 107 and 101 of the switch 102, wire 100, terminal 46, contact member 45, contact 44, bridge member 43, contact 47, contact member 48, contact 10 67, conductor 110, contact 72, conductor 111, contacts 80 and 81 of the overload cut-out 71, conductor 112, operating coil 69, conductor 113, and power terminal 86 back to the other line wire 89. Completion of this starting circuit energizes the 15 operating coil 69 to move the bridge member 70 into engagement with the maintaining contacts 71 and 72 and to move the bridge member 73 into engagement with the load contacts 74 and 75.

Movement of the bridge member 73 into engagement with the load contacts 74 and 75 completes a load circuit for the compressor motor 30 which may be traced as follows: from the line wire 88 through contact 65, conductor 116, terminal 79, heater 78, contact 74, bridge member 25 73, contact 75, wire 90, compressor motor 30, wire 91 and power terminal 86 back to the other line wire 89. Completion of this load circuit causes operation of the refrigerating apparatus.

Movement of the bridge member 70 into engagement with the maintaining contacts 71 and 72 completes a maintaining circuit for the operating coil 69 which is independent of the contact members 48 and 66 and this maintaining circuit may be traced from the line wire 88 to contact 35 65, contact member 63, terminal 64, wire 108, electrodes 107 and 101, wire 100, terminal 46, contact member 45, contact 44, bridge member 43, conductor 115, contact 71, bridge member 70, contact 72, conductor 111, contacts 80 and 81, 40 conductor 112, operating coil 69, conductor 113 and power terminal 86 back to the line wire 89. Completion of this maintaining circuit for the relay or starter 68 maintains the refrigerating apparatus in operation until either the temperature of the fixture 16 decreases to 38°, for example, the low pressure decreases to 20 pounds, or the high pressure increases to 185 pounds. After the compressor has been shut down upon the occurrence of any of these contingencies, it 50 cannot be again restarted until the high pressure decreases to 135 pounds, the low pressure increases to 35 pounds, and the temperature of the fixture 16 increases to 40°. By reason of this control arrangement the temperature of the fixture 16 is normally maintained within the desired limits of 38° to 40° and the defrosting occurs each time that the operation of the refrigerating apparatus is stopped, this defrosting taking place in all of the evaporators, since the bellows 35 60 responds to the suction pressure in the whole system and this suction pressure will not rise to 35 pounds until all of the evaporators have defrosted.

Located within the fixture 17 is a humidity 65 responsive device 125, this device comprising a humidity responsive element 126 of any conventional construction being suitably secured to a support at its lower end and having its upper end secured to one end of a lever 127, this lever being 70 biased in a direction which maintains the humidity responsive element elongated by means of a spring 128. Carried by the lever 127 is an arm 129 which is arranged to sweep over a potentiometer resistance 130. Upon an increase in 75

humidity within the fixture 17, the element 126 will expand and permit movement of the arm 129 to the right under the influence of the spring 128 and upon a decrease in humidity in the space 5 the arm 129 will move to the left by reason of the contraction of the element 126. The potentiometer 130 is arranged to control a motor 131 which may be a proportioning motor of the type illustrated in Patent No. 2,028,110 issued to D. G. 10 Taylor on January 14, 1936. The outer terminals of this motor are connected by means of conductors 132 and 133 to the extremities of the resistance 130 and the center terminal of the motor is connected by the conductor 134 to the slider 15 arm 129. Conductors 135 and 136 are provided for supplying power to the motor 131. Operated by the motor is a pinion 138 carried by the shaft 139 of the motor and upon reference to the Taylor patent, it will be apparent that movement 20 of the arm 129 with respect to the resistance 130 will cause rotation of the pinion 138 by an amount which is proportional to the movement of the arm 129. This motor 131 is provided for varying the superheat setting of the expansion 25 valve 20 in accordance with variations in humidity in the fixture 17 as will now be described.

The expansion valve 20 may be any one of the types shown in my copending application Serial No. 192,818, filed February 26, 1938. This valve 30 has provisions whereby the superheat setting thereof may be readily varied, there being an adjustable yoke 140 biased downwardly by means of a spring 141, the upper portion of the spring bearing against an adjusting nut 145 movable with 35 the valve, and the lower portion of the spring bearing against the lower portion of the yoke (not shown) and biasing the yoke downwardly, the yoke terminating in a rack 142 which meshes with the gear 138. The expansion valve is moved 40 in accordance with variations in superheat at the outlet of the evaporator, the operating parts of the valve responding to the pressure of the refrigerant leaving the evaporator and also responding to the pressure corresponding to the temperature 45 of the refrigerant leaving the evaporator. For this purpose a connection 143 is provided between the valve and the evaporator outlet by which variations in pressure are communicated to the operating portions of the valve. Within this connection 50 may be provided a capillary tube terminating in a bulb having a volatile fill which may be located within the outlet pipe of the evaporator 14 in order to communicate the effects of temperature variations in the evaporator outlet as shown in my copending application referred to above. As the rack 142 is moved upwardly against the force of the spring 141, it causes an increase in the superheat setting of 55 the valve which means that the valve will maintain a higher superheat at the outlet of the evaporator and a smaller portion of the evaporator will be filled with liquid refrigerant but this liquid refrigerant will be at a lower pressure so that while the temperature of the evaporator 60 is reduced by moving the rack 142 downwardly the effective cooling area thereof is at the same time decreased. By causing a reduction in the pressure of the refrigerant, the temperature of the other evaporator will also be reduced to increase the cooling effect thereof, and cause the 65 system to operate at maximum efficiency.

As the humidity in the fixture 17 rises and the arm 129 moves to the right, it will cause operation of the motor in a manner to cause upward movement of the rack 142 by an amount which

is proportional to the rise in humidity which will raise the superheat setting of the expansion valve 20 causing the evaporator 14 to operate at a higher superheat but at a lower coil temperature thus increasing the dehumidifying effect of 5 the evaporator 14. While I have shown the control of the expansion valve 20 in the fixture 17 by a humidity responsive device to maintain a predetermined humidity within the fixture, it will, of course, be obvious that this humidity responsive element might be replaced by a temperature responsive device if it were desired to maintain the temperature in the fixture at a predetermined value, in which case upon a rise in temperature in the space the rack 142 would be moved downwardly thus decreasing the superheat setting of the expansion valve whereupon the evaporator 14 would be operated at a lower superheat and a larger portion of the evaporator would be effective for sensible cooling. It will be understood 10 that the limit of the superheat maintained by any evaporator will be determined solely by the setting of the expansion valve for that evaporator.

Another way in which the control of the fixture temperature may be readily effected is illustrated in the fixture 18. The flow of refrigerant to the evaporator 15 in this fixture is shown as being controlled by the expansion valve 21 which may be any conventional type of thermostatic expansion valve whereupon the evaporator 30 will be operated at a substantially constant degree of superheat. A second valve 150 controls the flow of refrigerant to the expansion valve 21, the position of this valve 150 being controlled by an operating diaphragm 151. The pressure exerted on the diaphragm 151 is varied in accordance with the temperature in the fixture and for this purpose a bulb 152 may be located within the fixture and connected by means of a capillary tube 153 to the diaphragm chamber, this 35 tube, bellows and chamber being provided with a suitable fill such as a volatile fill whereupon it will increase or decrease in pressure in accordance with variations in temperature in the fixture 18 and in turn will cause movement of 40 the diaphragm 151 and the valve 150. Upon an increase in temperature in the fixture 18, the pressure exerted by the volatile fill will decrease and the valve 140 will move to a position wherein a greater flow of refrigerant to the expansion 45 valve 21 is permitted to increase the cooling effect of the evaporator 15. Thus the cooling effect of the evaporator 15 and the temperature of the fixture 18 may be readily controlled by operation of the valve 140 in the line leading to 50 the expansion valve 21.

The operation of this system will now be readily apparent. The fixture 16 may be the one having the greatest load requirements and may be a large fixture such as a walk-in box and for 55 this reason the temperature controller 106 is located therein. The other fixtures 17 and 18 may be for any suitable purpose such as display cases, water coolers, and the like, and having a lesser load requirement on the refrigeration system. As soon as the temperature within the fixture 16 rises sufficiently high and the suction pressure in the system rises sufficiently high, say to 40 pounds, at which pressure all the evaporators are defrosted, the compressor will be placed 60 in operation and refrigerant will be supplied to all of the evaporators. The temperature of the fixture 18 is controlled by controlling the valve 150 which controls the amount of refrigerant supplied to the expansion valve 21 and the hu- 65

midity or, if desired, the temperature of the fixture 17 is controlled by controlling the degree of superheat in the evaporator 14 by adjusting the superheat setting of the expansion valve 20.

- 5 As long as the temperature within the evaporator 16 is above the desired value, the compressor will continue operating unless the suction pressure in the system should fall below 20 pounds or the head pressure should rise above 185 pounds. It 10 is advisable to maintain the compressor in operation until the temperature in the fixture 16 drops to the desired value since this is the fixture that will normally require the greatest amount of cooling and it is therefore not desirable 15 to commence a defrosting cycle until the temperature of this fixture had dropped to the desired value. As soon as the thermostat in the fixture 16 is satisfied, however, the compressor will shut down and cannot be restarted until the 20 suction pressure throughout the system rises to 40 pounds, at which pressure all of the evaporators will be defrosted so that a defrosting cycle is assured between each operation of the compressor. The expansion valves operate to prevent flooding of the evaporators during the defrosting cycle since they operate to control the superheat at the outlets thereof.

It will be obvious that the temperature controller of the fixture 18 may take any desired 30 form and the valve 140 may be controlled by a proportioning motor as shown in the fixture 17 or in any other suitable manner. Suitable adjustments may be made so that the temperatures in the various fixtures or the humidity in the fixture 17 may be maintained at any desired value.

It will thus be seen that frequent defrosting of the system is assured without the use of any timing mechanism and without depending upon a plurality of fixture thermostats cycling together 40 since it is necessary for only the thermostat in the main fixture to become satisfied to initiate a defrosting operation and this is made possible by reason of the fact that the temperatures in the other fixtures are adjusted or controlled by controlling the flow of refrigerant into these other evaporators.

Having described a preferred form of my invention, it will be understood that many modifications 50 may be made therein and I therefore desire to be limited only by the scope of the appended claims.

I claim as my invention:

1. In a multiple fixture mechanical refrigerating apparatus having an evaporator for each fixture, a condenser and a compressor for circulating refrigerant through the evaporators, means responsive to the temperature of one of the fixtures for starting and stopping operation of the compressor to maintain desired temperature conditions within said fixture, means responsive to a condition to be controlled in another fixture for controlling the flow of refrigerant through the evaporator in that fixture to maintain the condition 60 therein at a desired value, and means for always preventing restarting of the compressor until all of the evaporators have been defrosted.

2. In a multiple fixture mechanical refrigerating apparatus having an evaporator for each fixture, a condenser and a compressor for circulating refrigerant through the evaporators, means responsive to the temperature of one of the fixtures for starting and stopping operation of the compressor to maintain desired temperature conditions within said fixture, suction pressure re-

sponsive means in control of said compressor for interrupting operation thereof whenever the suction pressure drops to a predetermined value, means responsive to a condition to be controlled in another fixture for controlling the flow of refrigerant through the evaporator in that fixture to maintain the condition therein at a desired value, and means for always preventing restarting of the compressor until all of the evaporators have been defrosted.

3. In a multiple fixture mechanical refrigerating apparatus having an evaporator for each fixture, a condenser and a compressor for circulating refrigerant through the evaporators, means responsive to the temperature of one of the fixtures for starting and stopping operation of the compressor to maintain desired temperature conditions within said fixture, means responsive to the temperature in another fixture for controlling the flow of refrigerant through the evaporator in that fixture to maintain the temperature therein at a desired value, and means for always preventing restarting of the compressor until all of the evaporators have been defrosted.

4. In a multiple fixture mechanical refrigerating apparatus having an evaporator for each fixture, a condenser and a compressor for circulating refrigerant through the evaporators, means responsive to the temperature of one of the fixtures for starting and stopping operation of the compressor to maintain desired temperature conditions within said fixture, means responsive to the humidity in another fixture for controlling the flow of refrigerant through the evaporator in that fixture to maintain the humidity therein at a desired value, and means for always preventing restarting of the compressor until the suction pressure has risen to a predetermined value whereby simultaneous defrosting of the evaporators is effected.

5. In a multiple fixture mechanical refrigerating apparatus having an evaporator for each fixture, a condenser and a compressor for circulating refrigerant through the evaporators, means responsive to the temperature of one of the fixtures for starting and stopping operation of the compressor to maintain desired temperature conditions within said fixture, suction pressure responsive means in control of said compressor for interrupting operation thereof whenever the suction pressure drops to a predetermined value, means responsive to the temperature in another fixture for controlling the flow of refrigerant through the evaporator in that fixture to maintain the temperature therein at a desired value, and means for always preventing restarting of the compressor until the suction pressure has risen to a predetermined value whereby simultaneous defrosting of all the evaporators is effected.

6. In a multiple fixture mechanical refrigerating apparatus having an evaporator for each fixture, a condenser and a compressor for circulating refrigerant through the evaporators, means responsive to the temperature of one of the fixtures for starting and stopping operation of the compressor to maintain desired temperature conditions within said fixture, suction pressure responsive means in control of said compressor for interrupting operation thereof whenever the suction pressure drops to a predetermined value, means responsive to the humidity in another fixture for controlling the flow of refrigerant through the evaporator in that fixture to main-

tain the humidity therein at a desired value, and means for always preventing restarting of the compressor until the suction pressure has risen to a predetermined value whereby simultaneous defrosting of all the evaporators is effected.

7. In a multiple fixture mechanical refrigerating apparatus having an evaporator for each fixture, a condenser and a compressor for circulating refrigerant through the evaporators, means re-

10 sponsive to the temperature of one of the fixtures for starting and stopping operation of the compressor to maintain desired temperature conditions within said fixture, thermostatic expansion valve means controlling the flow of refrigerant

15 through the evaporator in another fixture, means responsive to a condition to be controlled in that fixture for adjusting the superheat setting of said

20 valve means to control the flow of refrigerant thereto to maintain the condition in that fixture at a desired value, and means for always preventing restarting of the compressor until the suction pressure has risen to a predetermined value whereby simultaneous defrosting of all the evaporators is effected.

25 8. In a multiple fixture mechanical refrigerating apparatus having an evaporator for each fixture, a condenser and a compressor for circulating refrigerant through the evaporators, means re-

30 sponsive to the temperature of one of the fixtures for starting and stopping operation of the compressor to maintain desired temperature conditions within said fixture, thermostatic expansion valve means controlling the flow of refrigerant

35 through the evaporator in another fixture, a second valve means controlling the flow of refrigerant to said expansion valve means, means re-

40 sponsive to a condition to be controlled in that fixture for adjusting said second valve means whereby the flow of refrigerant through the evap-

45 orator in that fixture is properly controlled to maintain the condition therein at a desired value, and means for always preventing restarting of the compressor until the suction pressure has risen to a predetermined value whereby simultaneous de-

50 frosting of all the evaporators is effected.

9. In a multiple fixture mechanical refrigerating apparatus having an evaporator for each fixture, a condenser and a compressor for circulating refrigerant through the evaporators, means re-

55 sponsive to the temperature of one of the fixtures for starting and stopping operation of the compressor to maintain desired temperature conditions within said fixture, suction pressure re-

60 sponsive means in control of said compressor for interrupting operation thereof whenever the suc-

65 tion pressure drops to a predetermined value, thermostatic expansion valve means controlling the flow of refrigerant through the evaporator in another fixture, means responsive to a condition

70 to be controlled in that fixture for adjusting the superheat setting of said valve means to control the flow of refrigerant thereto to maintain the condition in that fixture at a desired value, and

75 means for always preventing restarting of the compressor until the suction pressure has risen to a predetermined value whereby simultaneous de-

80 frosting of all the evaporators is effected.

10. In a multiple fixture mechanical refrigerating apparatus having an evaporator for each fixture, a condenser and a compressor for circulating refrigerant through the evaporators, means re-

85 sponsive to the temperature of one of the fixtures for starting and stopping operation of the compressor to maintain desired temperature condi-

90 tions within said fixture, suction pressure respon-

sive means in control of said compressor for in-
95 terrupting operation thereof whenever the suc-
tion pressure drops to a predetermined value, thermostatic expansion valve means controlling
the flow of refrigerant through the evaporator in
another fixture, a second valve means controlling
100 the flow of refrigerant to said expansion valve
means, means responsive to a condition to be con-
trolled in that fixture for adjusting said second
valve means whereby the flow of refrigerant
through the evaporator in that fixture is properly
105 controlled to maintain the condition therein at a
desired value, and means for always preventing
restarting of the compressor until the suction
pressure has risen to a predetermined value
whereby simultaneous defrosting of all the evap-
110 orators is effected.

11. In a multiple fixture refrigerating appa-
115 ratus having an evaporator for each fixture, a con-

denser and a compressor for circulating refriger-
120 ant through the evaporators, control means for

said compressor, said control means including
125 means for starting the compressor whenever the
temperature in one of said fixtures rises above a
predetermined value, the suction pressure rises

130 above a value indicating that all of the evap-
orators are defrosted, and the head pressure on the
compressor drops below a predetermined value,
means for interrupting operation of the compres-

135 sor whenever the temperature in said one fixture
drops below a predetermined value, or when the
suction pressure drops below a predetermined val-

140 ue or the head pressure of the compressor rises
above a predetermined value, means for control-

145 ling the flow of refrigerant through the evap-
orator in another of said fixtures, and means re-

150 sponsive to a condition to be maintained in said
other fixture in control of said flow controlling
means.

12. In a multiple fixture refrigerating appa-
155 ratus having an evaporator for each fixture, a con-

denser and a compressor for circulating refriger-
160 ant through the evaporators, control means for

said compressor, said control means including
165 means for starting the compressor whenever the
temperature in one of said fixtures rises above a
predetermined value, the suction pressure rises

170 above a value indicating that all of the evap-
orators are defrosted, and the head pressure of the
compressor drops below a predetermined value,
means for interrupting operation of the compres-

175 sor whenever the temperature in said one fixture
drops below a predetermined value, or when the
suction pressure drops below a predetermined val-

180 ue or the head pressure of the compressor rises
above a predetermined value, thermostatic valve
means for controlling the flow of refrigerant
185 through the evaporator in another of said fixtures,
and means responsive to a condition to be

190 maintained in said other fixture for controlling
the superheat setting of said valve means.

13. In a multiple fixture refrigerating appa-
195 ratus having an evaporator for each fixture, a con-

denser and a compressor for circulating refriger-
200 ant through the evaporators, control means for

said compressor, said control means including
205 means for starting the compressor whenever the
temperature in one of said fixtures rises above a
predetermined value, the suction pressure rises

210 above a value indicating that all of the evap-
orators are defrosted, and the head pressure of the
compressor drops below a predetermined value,
means for interrupting operation of the compres-

215 sor whenever the temperature in said one fixture
drops below a predetermined value, or when the

- suction pressure drops below a predetermined value or the head pressure of the compressor rises above a predetermined value, thermostatic valve means for controlling the flow of refrigerant 5 through the evaporator in another of said fixtures, a second valve means for controlling the flow of refrigerant to said thermostatic valve means, and means responsive to the temperature in said other fixture for controlling the position 10 of said second valve means to maintain the temperature in said other fixture at a desired value.
14. In a multiple fixture mechanical refrigerating apparatus having an evaporator for each fixture, a condenser and a compressor for circulating 15 refrigerant through the evaporators, means responsive to the temperature of one of the fixtures for starting and stopping operation of the compressor to maintain desired temperature conditions within said fixture, means responsive to the 20 temperature in a second fixture for controlling the flow of refrigerant through the evaporator in that fixture to maintain the temperature therein at a desired value, means responsive to the humidity in a third fixture for controlling the flow of refrigerant through the evaporator in the third fixture to maintain the humidity therein at a desired value, and means for always preventing restarting of the compressor until the suction pres- 25
- sure has risen to a predetermined value whereby simultaneous defrosting of all the evaporators is effected.
15. In a multiple fixture mechanical refrigerating apparatus having an evaporator for each fixture, a condenser and a compressor for circulating refrigerant through the evaporators, means responsive to the temperature of one of the fixtures for starting and stopping operation of the compressor to maintain desired temperature conditions within said fixture, suction pressure responsive means in control of said compressor for interrupting operation thereof whenever the suction pressure drops to a predetermined value, means responsive to the temperature in a second fixture for controlling the flow of refrigerant through the evaporator in that fixture to maintain the temperature therein at a desired value, means responsive to the humidity in a third fixture for controlling the flow of refrigerant through the evaporator in the third fixture to maintain the humidity therein at a desired value, and means for always preventing restarting of the compressor until the suction pressure has risen to a predetermined value whereby simultaneous defrosting of all the evaporators is effected. 5 10 15 20 25
